UNITED STATES PATENT OFFICE

2,474,232

SAFETY CONTROL DEVICE

Max Dach, Flushing, N. Y.

Application July 14, 1944, Serial No. 544,971

32 Claims. (Cl. 123—98)

1

This invention relates to control apparatus for engines and more particularly when mounted in vehicles or machines propelled by engines.

In the operation of motor vehicles and particularly vehicles of the heavier type such as buses and trucks it is highly important to conserve the life of the engine and it is desirable that racing of a cold engine be avoided. It is likewise desirable that the engine be not operated beyond the maximum temperature.

In vehicles of the type having brakes dependent upon air pressure it is likewise important that the vehicle be not operated until sufficient air is available to control it.

It is an object of my invention to provide a multiple control means centered in a single element to make operation of a vehicle difficult but not impossible when the engine is cold, when the temperature is too high, when air pressure falls below a safety level, when the oil pressure drops below a predetermined minimum, or, when the doors are open, or when the engine speed or vehicle speed exceeds a predetermined maximum.

While there are numerous gages and devices to indicate to an operator any of the foregoing conditions these gages may be overlooked and a vehicle damaged or unnecessarily aged by a careless operator.

It is an object of this invention to arrange proper controls in a cooperating relationship whereby any one of the foregoing conditions will be forcibly brought home to the driver in such a way as to make operation of the vehicle difficult and to cause the driver to take steps to correct such a condition before any damage is done.

It is a further object to leave the vehicle in an operable condition so that it may be driven in spite of the controls and thus avoid the possibility of accidents due to stalling on tracks, the middle of the street, or elsewhere.

Other objects and advantages of my invention will become apparent from the accompanying drawing and the following description.

In the drawings—

Figure 1 shows a form of my invention applied to a temperature control and to the oil tank;

Fig. 2 shows a modification applied to maximum and minimum temperature units;

Fig. 3 shows a composite cooperative system in which all of the various controls are linked to a single indicating means;

Referring more particularly to the drawing, in Figure 1 thereof 10 indicates the accelerator which is pivoted at 11 and has the arm 12 pivoted at 13 with the rod 14 extending to the carburetor 15

2

and operating in the conventional manner. Mounted on the rod 14 is a depending lever 16 fastened thereto at 17 and designed to move with the rod 14. A cylinder 20 is mounted on a suitable support 21 and contains a piston 22 which would normally be pressed against the end 23 of the cylinder 20 by means of spring 24. Plunger 22 has a shaft 25 extending through the bracket 26 with a stop member 27 mounted thereon. Suitable tubing 30 leads from the end 23 of the cylinder 20 to a thermal element 31. The thermal element 31 is of the conventional type and may be controlled by a mercury tube or otherwise set to react at a predetermined temperature to close the valve 32 into its seat 33. Leading from the thermal unit 31 is a tube 35 connected to the compressed air tank 36. Where a single control based upon the pressure in the tank 36 is desired the thermal unit 31 may be eliminated and the tubing 30 connected directly to the tank 36. However, in the form shown, a dual control based on temperature and air pressure is presented.

It will be appreciated that as long as the temperature in the engine is below a dangerous maximum the valve 32 will remain open and air can pass from the tank into the cylinder 20. The spring 24 is of predetermined strength so that when sufficient pressure is in the tank 36 piston 22 will be pushed away from the end 23, thus allowing the lever 16 to move freely on the shaft 25 without interference from the stop 37. On the other hand, should the temperature be such as to close the valve 32 or should the pressure in the tank 36 drop below a predetermined minimum then the spring 24 will push the piston 22 to the end 23 of the cylinder and the operator, in order to depress the accelerator, will have to push against the strength of the spring 24 since the stop 27 will engage the lever 16.

It will thus be forcibly brought to the operator's attention that something is wrong since it will be necessary for him to exert a great deal of pressure upon the accelerator in order to operate the vehicle. By the same token, the vehicle will not be stalled since it will be possible for him to press against the strength of the spring 24.

In the form shown in Figure 2 the two thermal units 39 and 40 are shown, one set for a maximum temperature and the other for a minimum temperature. Assuming that the thermal unit 40 is set for a minimum temperature and such temperature is reached the piston 41 held by the spring 42 will move to the right and the arm 43 will be brought into contact with the arm 44 positioned on the rod or shaft 45 controlling the

carburetor 15. The accelerator 10 will then be difficult to operate. As shown in Figure 2 the arm 43 is shown in the operative position. The rod 45 and the rod 46 are linked together by the shaft 47 and the arms 48 and 49 so that the rods 45 and 46 move together. The unit 39 is set for a maximum temperature and will of course not be affected by cold registered by the unit 40. However, should the temperature rise above the predetermined maximum the piston 50 will be moved against the spring 51 and the arm 52 will be brought into the position shown by the dotted lines where it will engage the arm 54 when the accelerator 10 is depressed, thus forcing the operator to further compress the spring 51 to depress the accelerator and warning him of the danger.

In the form shown in Figure 3 a plurality of control units are linked to the common indicator, namely, the spring making the depression of the accelerator difficult. In this form the accelerator 60 pivoted at 61 has a series of links 62 connecting it with the carburetor. A spring element 63 is connected to the solenoid 64 which, when energized from the battery source 69, will push the spring 63 up against the accelerator to make operation difficult. In this circuit a number of control devices are set up. The air tank 65 is provided with a control element 66 of any conventional type adapted to close the circuit between the wires 67 and 68 when pressure of the tank falls below a predetermined level. A thermal unit 70 is provided to close the circuit between the wires 71 and 72 when a maximum temperature is reached. It will be appreciated that the thermal unit 70 may be arranged in pairs in a manner similar to that shown in Figure 2, one unit to take care of maximum and the other to take care of minimum pressures. A float 75 may be positioned in the crankcase 76 to close the contacts between the wires 77 and 78 when the oil in the crankcase falls below a predetermined level. Similarly a pressure gage 80 will close the circuit between the wires 81 and 82 should the pressure in the oil pump fall.

A governor 85 is provided to determine the number of revolutions a minute of the motor with the hand 86 set to close the circuit at a predetermined point by connecting the wires 87 and 88. The circuit may be closed by the opening of the door 90 on the hinge 91 by any conventional means, such as the spring plunger 92 adapted to connect the contacts 93 and 94 by means of the bridge 95 when the door 90 is moved away from the jamb 96.

It will be appreciated that I have provided a series of controls cooperatively connected in one circuit to the solenoid 64 which controls the spring 63 and will bring it into active engagement with accelerator 60. Should there be defects in any one of the controls set by falling air pressure, overheating or cold motor, lack of oil in the crankcase, falling oil pressure in the motor, or racing of the motor, any one case the circuit will be closed, the solenoid will move the spring 63 into engagement with the accelerator 60 and the operator will only be able to depress the accelerator with difficulty. The same is true of the door 90. If the door is open or not completely closed it will be difficult for the operator to depress the throttle. The average vehicle is provided with temperature controls and pressure gages, oil gages, and in many instances light controls that show whether or not the door is open or closed. When the operator encounters difficulty and this difficulty is brought home to him

through the throttle he will then be forced to check his other controls to determine where the difficulty lies and the danger of ruining the engine of a vehicle is eliminated.

5 While my device brings any fault forcibly to the driver's attention it does not completely immobilize the vehicle and there is no danger of the vehicle being immobilized on a railroad crossing or in traffic since the driver may, by exerting extraordinary pressure on the accelerator, depress the spring 63 and move the vehicle out of danger.

I claim:

1. In combination with an accelerator, means for making the operation of said accelerator difficult, said means including a piston, a spring normally pushing said piston, a shaft on said piston, an arm associated with said accelerator, and a stop on said shaft adapted to engage said arm, tubing connecting said cylinder with an air tank to force said piston against said spring and to move said stop out of engagement with said arm when the pressure in said tank is above predetermined pressure.

2. In combination with a machine having an accelerator, an air tank and a thermostatic control, of a cylinder, a piston in said cylinder, a spring yieldingly pushing said piston toward one end of said cylinder, a shaft on said piston, means for operatively connecting said accelerator to said shaft when said piston is moved to one end of said cylinder by said spring, a line connecting the end of said cylinder with said air tank, and a valve controlled by said thermostat in said line between said tank and said cylinder.

3. The combination with a machine having an accelerator and an air-tank of a cylinder, a line connecting the end of said cylinder with said air-tank, a piston in said cylinder, a spring yieldingly pushing said piston toward the end of said cylinder, a shaft on said piston and means for operatively connecting said accelerator to said shaft when the air pressure in said tank is below a predetermined pressure and said piston is moved to the end of said cylinder by said spring.

4. The combination with a machine having an accelerator of a cylinder, a piston in said cylinder, a spring yieldingly pushing said piston towards the end of said cylinder, a shaft on said piston and normally free of the accelerator, and means operatively connecting said accelerator to said shaft when said piston is moved to one end of said cylinder by said spring.

5. The combination with a machine having an accelerator of a cylinder, a piston in said cylinder, a spring yieldingly pushing said piston towards the end of said cylinder, a shaft on said piston, and normally free of connection with the accelerator, means operatively connecting said accelerator to said shaft when said piston is moved to one end of said cylinder by said spring, and means for moving said piston against said spring under pre-determined conditions.

6. Means for association with power means, wherein the power means has means for varying the power output of such power means, and the power means has certain minimal requirements for efficient operation, and the varying means includes means for bringing the varying means normally to idling position; the means for association with the power means comprising means for interposing resistance to movement of the varying means out of idling position to increase the power output but without preventing movement of the varying means out of said idling

position, and means for disabling the resistance-interposing means when the minimal requirements are satisfied.

7. In combination with an internal combustion engine, means for varying the power output of the engine, the engine having certain minimal requirements for efficient operation, means for bringing the varying means normally to idling position; means for interposing resistance to movement of the varying means out of idling position to increase the power output of the engine but without preventing movement of the varying means out of said idling position; and means for disabling the resistance-interposing means when the minimal requirements are satisfied.

8. In combination with power means, means for varying the power output of such power means, the power means having certain minimal requirements for efficient operation, means for bringing the varying means normally to idling position, means for interposing resistance to movement of the varying means out of idling position to increase the power output but without preventing movement of the varying means out of said idling position; and means for disabling the resistance-interposing means when the minimal requirements are satisfied.

9. Means for association with an internal combustion engine, wherein the engine has means for varying the power output of the engine, and the engine has certain minimal requirements for efficient operation, and the varying means includes means for bringing the varying means normally to idling position; the means for association with the engine comprising means for interposing resistance to movement of the varying means out of idling position to increase the power output but without preventing movement of the varying means out of said idling position, and means for disabling the resistance-interposing means when the minimal requirements are satisfied.

10. Means for association with an internal combustion engine, wherein the engine has a throttle for controlling the power output of the engine, and the engine has certain minimal requirements for efficient operation, and the throttle has means for bringing the throttle normally to idling position; the means for association with the engine comprising means for interposing resistance to movement of the throttle out of idling position to increase the power output of the engine but without preventing movement of the throttle out of said idling position, and means for disabling the resistance-interposing means when the minimal requirements are satisfied.

11. Means for association with power means, wherein the power means has means for varying the power output of such power means, and the power means has certain minimal requirements for efficient operation, and the varying means includes means for bringing the varying means normally to idling position; the means for association with the power means comprising compressible means for interposing resistance to movement of the varying means out of idling position to increase the power output but without preventing movement of the varying means out of said idling position, and means independent of the varying means for compressing the compressible means to make the compressible means ineffective when the minimal requirements are satisfied.

12. Means for association with an internal

combustion engine, wherein the engine has means for varying the power output of the engine, and the engine has certain minimal requirements for efficient operation, and the varying means includes means for bringing the varying means normally to idling position; the means for association with the engine comprising compressible means for interposing resistance to movement of the varying means out of idling position to increase the power output but without preventing movement of the varying means out of said idling position; and means independent of the varying means for compressing the compressible means to make the compressible means ineffective when the minimal requirements are satisfied.

13. Means for association with an internal combustion engine, wherein the engine has a throttle for controlling the power output of the engine, and the engine has certain minimal requirements for efficient operation, and the varying means includes means for bringing the throttle normally to idling position; the means for association with the engine comprising compressible means for interposing resistance to movement of the throttle out of idling position to increase the power output but without preventing movement of the throttle out of said idling position, and means independent of the throttle for compressing the compressible means to make the compressible means ineffective when the minimal requirements are satisfied.

14. Means for association with an internal combustion engine, wherein the engine has a throttle for controlling the power output of the engine, and the throttle has a normal idling position for development of minimum power output, and the engine has certain minimum requirements for proper operation; the means for association with the engine comprising means for detecting variations in such requirements, means for normally resisting movement of the throttle out of idling position to increase the power output but without preventing actuation of the throttle out of said idling position, and means controlled by the detecting means for disabling the resisting means when the minimum requirements are satisfied.

15. Means for association with an internal combustion engine, wherein the engine has a throttle for controlling the power output of the engine, and the throttle has a normal idling position for development of minimum power output, and the engine has certain minimum requirements for proper operation; the means for association with the engine comprising means for detecting variations in such requirements, resilient means for normally resisting movement of the throttle out of idling position to increase the power output but without preventing actuation of the throttle out of said idling position, and means controlled by the detecting means for disabling the resilient means when the minimum requirements are satisfied.

16. Means for association with an internal combustion engine, wherein the engine has a throttle for controlling the power output of the engine, and the throttle has a normal idling position for development of minimum power output, and the engine has certain minimum requirements for proper operation; the means for association with the engine comprising means for detecting variations in such requirements, compressible resilient means for normally resisting

movement of the throttle out of idling position to increase the power output but without preventing actuation of the throttle out of said idling position, and means controlled by the detecting means for compressing the resilient means and retaining the resilient means compressed when the minimum requirements are satisfied.

17. Means for association with an internal combustion engine, wherein the engine has a throttle for controlling the power output of the engine, and the throttle has a normal idling position for development of minimum power output, and the engine has certain minimum requirements for proper operation; the means for association with the engine comprising means for detecting variations in such requirements, means for interposing a great force to resist and prevent the normal actuation of the throttle by the operator of the engine away from said idling position except by the exertion of a great force by the operator, and means controlled by the detecting means for disabling the force-interposing means when the minimum requirements are satisfied.

18. Means for association with an internal combustion engine, wherein the engine has a throttle for controlling the power output of the engine, and the throttle has a normal idling position for development of minimum power output, and the engine has certain minimum requirements for proper operation; the means for association with the engine comprising means for detecting variations in such requirements, a spring disposed for interposing a great force to resist and prevent the normal actuation of the throttle by the operator of the engine away from said idling position except by the exertion of a great force by the operator, and means controlled by the detecting means for making the spring ineffective to resist actuation of the throttle when the minimum requirements are satisfied.

19. Means for association with an internal combustion engine, wherein the engine has a throttle for controlling the power output of the engine, and the throttle has a normal idling position for development of minimum power output, and the engine has certain minimum requirements for proper operation; the means for association with the engine comprising means for normally resisting movement of the throttle out of idling position to increase the power output but without preventing actuation of the throttle out of said idling position, and pneumatic means responsive to variations in the requirements of the engine for disabling the resisting means when the minimum requirements are satisfied.

20. Means for association with an automotive vehicle, wherein the vehicle carries an internal combustion engine, and wherein the engine has a throttle for controlling the power output of the engine, and the throttle has a normal idling position for development of minimum power output, and wherein the vehicle has a source of air pressure for effecting certain operations of the vehicle, and wherein the engine and the vehicle have certain minimum requirements for proper operation including the air pressure available from said source; the means for association with the vehicle comprising means for responding to variations in such requirements, means for normally resisting movement of the throttle out of idling position to increase the power output but without preventing actuation of the throttle out of said

idling position, and means controlled by the responding means for disabling the resisting means when the minimum requirements are satisfied.

21. Means for association with an automotive vehicle, wherein the vehicle carries an internal combustion engine, and wherein the engine has a throttle for controlling the power output of the engine, and wherein the throttle has a normal idling position for development of minimum power output, and wherein the vehicle has a source of air pressure for effecting certain operations of the vehicle, and wherein the engine and the vehicle have certain minimum requirements for proper operation including the air pressure available from said source; the means for association with the vehicle comprising means for responding to variations in such requirements, means for normally resisting movement of the throttle out of idling position to increase the power output but without preventing actuation of the throttle out of said idling position, and pneumatic means controlled by the responding means for disabling the resisting means when the minimum requirements are satisfied.

22. Means for association with an automotive vehicle, wherein the vehicle carries an internal combustion engine, and wherein the engine has a throttle for controlling the power output of the engine, and wherein the throttle has a normal idling position for development of minimum power output, and wherein the vehicle has a source of air pressure for effecting certain operations of the vehicle, and wherein the engine and the vehicle have certain minimum requirements for proper operation including the air pressure available from said source; the means for association with the vehicle comprising means for normally resisting movement of the throttle out of idling position to increase the power output but without preventing actuation of the throttle out of said idling position, and pneumatic means controlled by air under pressure from said source and responsive to variations in the requirements of the engine for disabling the resisting means when the minimum requirements are satisfied.

23. Means for association with an automotive vehicle, wherein the vehicle carries an internal combustion engine, and wherein the engine has a throttle for controlling the power output of the engine, and wherein the throttle has a normal idling position for development of minimum power output, and wherein the vehicle has a source of air pressure for effecting certain operations of the vehicle, and wherein the engine and the vehicle have certain minimum requirements for proper operation including the air pressure available from said source; the means for association with the vehicle comprising a spring disposed for interposing a great force to resist and prevent the actuation of the throttle by the operator of the vehicle away from said idling position except by the exertion of a great force by the operator, and pneumatic means controlled by air under pressure from said source and responsive to variations in the requirements of the engine for making the spring ineffective to interpose its resistance to the actuation of the throttle when the minimum requirements are satisfied.

24. Means for association with an automotive vehicle having a power unit and a source of fluid under pressure mounted thereon, wherein the power unit has power-output-varying means, and wherein the varying means normally assumes an

idling position for development of minimum output, and wherein the vehicle including the power unit and the fluid pressure source has certain minimum requirements for proper operation; the means for association with the vehicle comprising means for interposing a large resistance to the normal operation of the varying means out of its idling position, and means responsive to the attainment of said certain minimum requirements for disabling the resistance-interposing means when the certain minimum requirements are attained.

25. Means for association with an automotive vehicle having a power unit and a source of fluid under pressure mounted thereon, wherein the power unit has power-output-varying means, and wherein the varying means normally assumes an idling position for development of minimum output, and wherein the vehicle including the power unit and the fluid pressure source has certain minimum requirements for proper operation; the means for association with the vehicle comprising means for interposing a large resistance to the normal operation of the varying means out of its idling position, and means energized by fluid under pressure from said source and responsive to the attainment of said certain minimum requirements for disabling the resistance-interposing means when the certain minimum requirements are attained.

26. Means for association with an automotive vehicle having a power unit and a source of fluid under pressure mounted thereon, wherein the power unit has power-output-varying means, and wherein the varying means normally assumes an idling position for development of minimum output, and wherein the vehicle including the power unit and the fluid pressure source has certain minimum requirements for proper operation; the means for association with the vehicle comprising means for interposing a large resistance to the normal operation of the varying means out of its idling position, and means energized by fluid under pressure from said source for disabling the resistance-interposing means.

27. Means for association with an automotive vehicle having a power unit and a source of fluid under pressure mounted thereon, wherein the power unit has power-output-varying means, and wherein the varying means normally assumes an idling position for development of minimum output, and wherein the vehicle including the power unit and the fluid pressure source has certain minimum requirements for proper operation; the means for association with the vehicle comprising a spring, means positionable by the spring to interpose the resistance of the spring to the normal operation of the varying means out of its idling position, and means responsive to the attainment of said certain minimum requirements for making the spring ineffective to position the resistance-interposing means when the certain minimum requirements are attained.

28. Means for association with power means, wherein the power means has means for controlling the increase of the power output of such power means, and wherein the power means has certain minimal requirements for efficient operation, and wherein the controlling means has means for positioning it in idling position for development of minimum output; the means for association with the power means comprising means for opposing actuation of the controlling means out of said idling position, the controlling

means being capable of actuation by an operator to increase the output above said minimum output but only by the exertion of great physical force, and means made effective when said minimal requirements are satisfied to disable the actuation-opposing means.

29. Means for association with power means, wherein the power means has means for controlling the increase of the power output of such power means, and wherein the power means has certain minimal requirements for efficient operation including the temperature developed in said power means, and wherein the controlling means has means for positioning it in idling position for development of minimum output; the means for association with the power means comprising means for opposing actuation of the controlling means out of said idling position, the controlling means being capable of actuation by an operator to increase the output above said minimum output but only by the exertion of great physical force, and means made effective when said minimal requirements including said temperature are satisfied to disable the actuation-opposing means.

25 30. Means for association with a vehicle, wherein the vehicle carries power means for propelling the vehicle and a source of fluid pressure for apparatus associated with the vehicle, and wherein the power means has means for control-

30 ling the increase of the power output of such power means, and wherein the power means and the pressure source have certain minimal requirements for the efficient operation of the vehicle, and wherein the controlling means has means

35 and wherein the controlling means has means for positioning it in idling position for development of minimum output; the means for association with the power means comprising means for opposing actuation of the controlling means out of said minimum output position, the con-

40 out of said minimum output position, the controlling means being capable of actuation by an operator to increase the output above said minimum output but only by the exertion of great physical force, and means made effective when
45 said minimal requirements are satisfied to disable the actuation-opposing means.

31. Means for association with a vehicle, wherein the vehicle carries power means for propelling the vehicle and a source of fluid pressure for apparatus associated with the vehicle, and wherein the power means has means for controlling the increase of the power output of such power means, and wherein the power means and the pressure source have certain minimal requirements for the efficient operation of the vehicle, and wherein the controlling means has means for positioning it in idling position for development of minimum output; the means for association with the power means comprising means for 50 opposing actuation of the controlling means out of said minimum output position, the controlling means being capable of actuation by an operator to increase the output above said minimum output but only by the exertion of great physical force, and means to make said pressure source effective when said minimal requirements are satisfied to disable the actuation-opposing means.

32. Means for association with a vehicle,
70 wherein the vehicle carries power means for pro-
pelling the vehicle and a source of fluid pressure
for apparatus associated with the vehicle, and
wherein the power means has means for con-
trolling the increase of the power output of such
75 power means, and wherein the power means and

the pressure source have certain minimal requirements for the efficient operation of the vehicle including the temperature developed in said power means, and wherein the controlling means has means for positioning it in idling position for development of minimum output; the means for association with the power means comprising means for opposing actuation of the controlling means out of said minimum output position, the controlling means being capable of actuation by an operator to increase the output above said minimum output but only by the exertion of great physical force, and means controlled by said temperature to make said pressure source effective when said minimal requirements including said temperature are satisfied to disable the actuation-opposing means.
